JOSEPH TRENT, OF MILLERTON, NEW YORK.

Letters Patent No. 86,713, dated February 9, 1869.

IMPROVED VOLUTE SPRING.

The Schedule referred to in these Letters Patent and making part of the same.

To all whom it may concern:

Be it known that I, JOSEPH TRENT, of Millerton, in the county of Dutchess, and State of New York, have invented a new and improved Coiled or Volute Spring, which I term a semi-elliptic volute spring; and I do hereby declare that the following is a full, clear, and exact description of the same, reference being had to the accompanying drawing, which forms part of this specification.

This invention relates to that class of springs termed volute springs, of which I will mention four kinds, the single or old-fashioned volute spring, the double or Rollins volute spring, the double or Freeland & Ward volute spring, and the quadruple or Trent volute spring. All of these are made by coiling or rolling up, usually around a mandrel, a plate, or strip of metal, of a certain definite shape.

It has been demonstrated that strips of different forms and shapes, when rolled or coiled up, constitute springs of different qualities and powers; hence the practical utility of the spring is not really due to the manner of coiling the sheet or strip, but to the peculiar shape of the strip or plate of metal used to make the spring; therefore the shape given to the strip constitutes an invention, inasmuch, as before stated, strips of different shapes produce springs possessing widely different powers and modes of operation.

My present invention consists in a new article of manufacture, to wit, a spring constructed of a strip of metal, which, before it is coiled or rolled up, is, as to a portion of its length, semi-elliptical, or nearly so, in shape or form, and which spring, when so made, may properly be termed a semi-elliptical volute spring.

In the accompanying drawing—

Figure 1 is a side elevation of the strip of metal, which, when coiled or rolled up, constitutes the spring.

Figure 2 is a side elevation of the spring which forms the subject of this application for patent.

Figure 3 is a vertical central section of the said spring.

A designates the plate or strip of metal used to construct the spring.

Said strip is semi-elliptical in shape, as to its main portion, *a*, and has two horizontal legs or arms, *b*, *b'*, one at each terminus of the semi-elliptical portion, *a*. One of these legs, *b*, is represented as of greater length than the other, *b'*, and when the strip is coiled, it produces an even base for the spring, the shorter leg, *b'*,

constituting the core of the spring; and I will remark that this shorter leg, *b'*, is not absolutely essential, though I find it preferable to terminate the strip in such way.

It is evident that a great number of these strips can be stamped out of a series of metallic plates by an ordinary metal-cutting press, and it is also obvious that in cutting a number of the strips out of a sheet, there will be but little waste of metal, inasmuch as the strip is of such shape that the knife, by one descent, cuts not only the lower edge of one strip, but the upper edge of the next succeeding strip; hence seven knives, arranged parallel with each other, will cut five strips, the only waste metal being at the top and bottom corners of the sheet. This is really an important advantage gained in the manufacture of such springs.

The strip, when cut, may be rolled up or coiled in any suitable manner. The usual practice, as hereinbefore stated, is to coil them around a mandrel, in a manner well known to those skilled in the art.

The operation of this spring, when subjected to weight, is as follows:

The upper coils are first depressed, an easy springing motion being produced. The flexibility of the spring having been exhausted as to these coils, a united action of these coils sinking downward on the core, (the latter pressing on the plate or base on which the spring rests,) takes place. The compression of these parts increases in proportion to the weight on the spring. This will be fully understood by referring to fig. 3, where the position of the coils before any compression takes place is illustrated.

A spring of the character herein described will securely maintain its vertical position, there being no liability of its "doubling," as with a double volute spring, and, moreover, the advantages of the strongest form of any known spring—that is, of an elliptical or semi-elliptical spring—are embodied in this spring.

What I claim as my invention, and desire to secure by Letters Patent, is—

As a new article of manufacture, a coiled or volute spring, which I term a semi-elliptic volute spring, constructed in the manner herein set forth.

JOSEPH TRENT.
